DOOR LOCK

Paul Niederdrenk, Velbert, Germany

Application July 22, 1937, Serial No. 155,128
In Germany November 12, 1936

2 Claims. (Cl. 70—143)

This invention relates to improvements in door locks or more particularly to a bolt and its operating mechanism so as to lock said bolt in its full or half stroke locking position. Compared with known devices of this type of locks the improved mechanism has the advantage that the full stroke of the bolt may be chosen considerably longer than was heretofore possible, so that an always secure locking of a door is assured. The securing of the bolt in its half or full stroke position has been rendered also more reliable, as an automatic or unintentional release of the bolt is not possible. This has been achieved by securing the bolt in its respective positions, i. e. half or full stroke, by means of a locking pin adapted to engage notches provided in the bolt body, which latter is actuated by a cam disk connected with a turning knob or key.

In the accompanying drawings the improved bolt with locking mechanism according to the present invention is illustrated by way of example, it shows:

Fig. 1 a vertical longitudinal section of the lock with the bolt secured in half stroke position,

Fig. 2 a similar section of the lock with the bolt pushed back, i. e. open position,

Fig. 3 a similar section of the lock on its locking stroke, being disengaged from the locking pin,

Fig. 4 a similar section of the lock with the bolt in completed end stroke in locked position,

Fig. 5 a horizontal section on line 5—5 of Fig. 4 and

Fig. 6 a vertical section on line 6—6 of Fig. 1.

Figs. 7—10 illustrate details.

Referring to the drawing 3 represents the bolt, slideably disposed in the lock cramp 1 of the box 2 against the action of two helical springs 4, disposed on guide bars 6 rigidly connected with the bolt head, said guide bars themselves being guided in a transverse rib 7 disposed within the box 2. The bolt body 5 is provided with a cam slot 8 adapted for right and left application of the lock, said cam slot 8 serving for the reception of a bolt driving pin 9 fixed onto a cam disk 12 operable by a knob 10, 11, said bolt driving pin 9 being under the influence of a spring 13.

15 designates a latch, movably mounted on a pin 14 and disposed below the cam disk 12, said latch 15 being provided with a locking pin 16. The latch 15 is subjected to the influence of a pressure spring 17, which tends to urge said latch and consequently also the locking pin provided thereon in direction against the bolt body 5, which is provided on one side edge with two notches 18,

19. These notches may also be provided on both side edges of the bolt body so as to be able to use the lock for right and left application. The locking pin 16 secures the bolt in position after its completed stroke or half ways by engaging 5 with the notch 19 and 18 respectively. The notch 18 is provided with a slanting side edge 20, by means of which an automatic release of the locking pin 16 is effected on the back stroke 10 of the bolt. The cam disk 12 with the bolt driving pin 9 is operated by turning the knob 10 connected with said cam disk, by which turning of the knob the bolt can be withdrawn. In order to prevent the bolt from being drawn back too far a stop pin 21 is provided on the inner box wall, 15 against which stop pin a nose-like projection 25, provided on the cam disk, abuts. As shown in Fig. 5 the bolt may also be operated by means of a key 23.

The operation of the lock according to the invention is as follows:

If the bolt 3 is in its fully advanced locking position as shown in Fig. 4, the locking pin 16 engages the notch 19, thus securing the bolt in its position. On actuating the cam disk 12 and 25 consequently also the bolt driving pin 9, attached thereto, by turning the knob 10, 11, the cam disk 12 forces the locking pin 16 out of the notch 18, whereby simultaneously the bolt is completely withdrawn by the pin 9, thus a door 30 with the lock attached thereto may be opened. On releasing the knob 10, the bolt shoots forwardly till the locking pin 16, by means of the spring influenced latch 15, is caused to engage to notch 18, whereby the bolt is secured in its half 35 way position (see Fig. 1). Now, on shutting the door, the bolt is caused to move backwards by the pressure against the bolt-nab, whereby the locking pin 16, sliding along the slanting side edge 20 of the notch 18, is automatically released 40 so that the bolt is permitted to shoot forwardly (see Fig. 2). During this advance of the bolt the pin 16 is prevented by the cam disk 12 from engaging the notch 18 by reason of said cam disk at this moment having not returned yet in 45 its normal position.

I claim:

1. The combination in a door lock, of a bolt, said bolt comprising a bolt head, two guide bars and a bolt body, said bolt body being provided 50 with two notches on its side edges and with a cam slot, helical springs disposed around the said guide bars, a cam disk with a driving pin attached thereto, said driving pin engaging said cam slot, a latch with a stop pin, said stop pin 55

adapted to engage with the notches of the bolt body, a means for actuating the cam disk, said cam disk on being actuated depressing said lock pin and a spring for urging the lock pin of the latch into the notches of the bolt body.

5 2. The combination in a door lock, of a bolt, said bolt comprising a bolt head, two guide bars and a bolt body, said bolt body being provided with two stop notches on each of its side edges, 10 one notch on each side edge having a slanting side edge, a cam slot provided in the bolt body,

helical springs disposed around said guide bars, a cam disk with a driving pin attached thereto, said driving pin engaging said cam slot, a latch with a stop pin, said stop pin adapted to engage the notches of the bolt body to secure the bolt in position and being acted upon by said cam disk, a spring acting upon said latch for urging the lock pin in locking position and means for operating said cam disk.
